UNITED STATES PATENT OFFICE.

AUGUST KEHM, OF CHICAGO, ILLINOIS.

RADIATOR SUPPORT.

Application filed January 13, 1919. Serial No. 270,856.

To all whom it may concern:

Be it known that I, AUGUST KEHM, a citizen of the United States, and resident of Chicago, county of Cook, and State of Illinois, have invented certain new and useful Improvements in Radiator Supports, of which the following is a specification, and which are illustrated in the accompanying drawings, forming a part thereof.

10 The invention relates to supports for radiators, particularly those radiators which are formed in panels and are commonly known as wall radiators. While these so-called wall radiators provide both a convenient and 15 effective means for heating large halls or rooms and for the circulation of the cold brine in the cooling rooms of cold storage warehouses and the like, such installations commonly require the use of a large number 20 of the panels or sections and it is frequently desirable to support the panels in horizontal rows or tiers, arranged at different levels. Similarly, it is sometimes desirable to support these radiators from the ceiling with 25 the panels in upright position in parallel rows at different levels and with a plurality of rows of panels at each level.

The object of the invention is accordingly to provide a support for wall radiators having provision for engagement with the panels or sections of the radiator in a plurality of different rows or tiers. A detail of the invention further provides for supporting the radiator panels of different rows or 35 tiers in suitably spaced relation to prevent the closing of the intervening spaces with accumulations of frost when the radiators are employed for the circulation of cold brine.

40 In the accompanying drawings;—

Fig. 1 is an end elevation of a wall radiator comprising three rows of panels arranged at different levels and shows one form of support provided by the invention 45 engaged with the panels of the radiator in all three of the said rows,

Fig. 2 is a detail front elevation of the apparatus illustrated in Fig. 1,

Fig. 3 is a detail sectional view taken on 50 the line 3—3 of Fig. 2,

Fig. 4 is similar to Fig. 3 but shows one form of construction which may be employed when the adjacent edges of the radiator sections in different rows are to be separated a sufficient distance to prevent clos-

ing of the intervening space with accumulations of frost,

Fig. 5 shows in side elevation a form of the improved radiator support which may be used when a refrigerating radiator comprising two rows of panels at each of two different levels is to be suspended from the ceiling, the radiator panels being shown in section and the spacing element being of a different form from that shown in Fig. 4, 65

Fig. 6 is a detail front elevation of the apparatus illustrated in Fig. 5,

Fig. 7 is a detail sectional view taken on the line 7—7 of Fig. 2, and

Fig. 8 is similar to Fig. 7 but shows a modified form of construction which may be used when the upper edge of the radiator is located immediately below a projecting window sill or the like.

In the form of construction illustrated in 75 Figs. 1, 2, 3 and 7, an upright wall plate in the form of a metal strap 10 is secured against the wall and extends from the floor level, indicated at 11, to a point slightly above the level of the upper edge of the 80 highest section 12 of the radiator 13. It will be understood that similar straps are secured against the wall at intervals throughout the length of the radiator and that only one is shown in the drawings to promote 85 simplicity of illustration. The extension of all of the said straps from the floor level 11 provides a convenient arrangement for insuring that all are located at the same elevation whereby a suitable inclination of the 90 radiator 13 for drainage is readily accomplished by adjustment of the several radiator supporting elements, as 14, 15, 16 with respect to the corresponding straps. The radiator 13 is shown as comprising, in addition 95 to the upper section 12, a lower section 17 and an intermediate section 18.

The radiator supporting elements or saddle blocks 14, 15, 16, are preferably of like construction and all are adjustably connected to the wall plate or strap 10 in the same manner. As shown, each comprises a shouldered clamping bolt 19 between the head and shoulder of which are mounted a pair of antifriction rollers 20, 21, and an intermediate bushing 22. The remainder of the bolt 19 carries a toothed spacing element 23, a clamping nut 24 and between these parts the bolt is engaged with the vertically slotted front wall of a chambered base block 110

25. Preferably, the front wall of the base block 25 is serrated, as at 26 (Fig. 3) for coaction with the toothed face of the spacing element 23 in any vertically adjusted position of the clamping bolt 19. The base blocks 25 may be secured against the strap 10 in any convenient manner but this is readily accomplished with certain of the anchor bolts, as 28, 29, 30, by which the strap 10 is secured against the wall. As shown, each of the anchor bolts 28, 29, 30, passes through one of the base blocks 25, at its upper end while the lower end of each base block 25 is formed with a stud 31 which enters a socket 32 in the strap.

10 15 Each of the radiator sections, as 12, 17, 18, rests with its lower edge upon the anti-friction rollers, 20, 21, of one of the supporting elements 14, 15, 16. Furthermore, 20 when the several radiator sections occupy relative positions corresponding with the compact arrangement illustrated in Figs. 1 and 2, the upper edge of each of the two lower radiator sections 17, 18, enters the 25 space between the two antifriction rollers 20, 21, of the supporting element 15 or 16 immediately above. It will thus appear that each of the intermediate supporting elements 15, 16, serves both for guidedly supporting 30 the radiator section, as 12 or 18, above it and also for guiding the radiator section 17 or 18 below it. The engagement of the upper edges of the radiator sections, as 17, 18, with the antifriction rollers 20, 21, of the supporting elements 15, 16, above the same is, 35 however, sufficiently loose not to interfere with the turning of these rollers during expansion and contraction of the radiator sections, as 12, or 18, which rest directly upon them. When the radiator is to be supplied 40 with cold brine for refrigeration, an arrangement providing relatively wide spaces, not only between adjacent sections, as 33, 34, (Fig. 4) but also between adjacent arms or 45 columns, as 35, 36, (Fig. 6) within each section, is required. Under these circumstances it becomes impractical for the upper edge of one section, as 33, (Fig. 4) to be directly engaged with the rollers 20, 21, which support 50 the section, as 34, next above. If desired, however, a member 37 which is forked at its lower end for guiding the upper edge of the lower section 33 may be hung upon the clamping bolt 19 of the corresponding 55 supporting element, as 15, between the rollers 20, 21, in place of the bushing 22 (Fig. 3). Obviously, the guide member 37 may be of the required length between its ends to correspond with the desired spacing of the sections, as 33, 34.

60 When the radiator, as 38, is to be suspended from the ceiling, as in Figs. 5 and 6, it will frequently comprise double rows of upper and lower sections, as 39, 40, 41, 42. 65 Under these circumstances, the improved

support preferably comprises a bearing plate 43, in strap form, similar to the wall plate 10 of the support already described, but extended at its upper end for connection with an overhead support, as at 44. As shown, 70 the bearing plate 43 is located between the two rows of upper and lower sections 39, 40, 41, 42, and is equipped at both sides with two sets of supporting elements 45, 46, 47, 48. The lower supporting elements 75 45, 47, are each identical in all respects with the supporting element 14 (Fig. 1). These are secured upon the bearing plate 43 by a common bolt 49 which passes through the same and through the base blocks 25 of both 80 supporting elements.

Similarly, the supporting elements 46, 48, are similar to the supporting elements 45, 47, and are secured to bearing plate 43 in the same manner, but each of the supporting 85 elements 46, 48 carries a forked member 50 for guidedly engaging the upper edge of the corresponding lower section 39 or 41. In this instance each guiding member 50 is hung from the corresponding clamping bolt 90 19, its position upon the bolt being immediately over the corresponding spacing element 23.

In each case the upper sections, as 12 (Fig. 1) and 40, 42 (Fig. 5) of the radiator 95 must be guided at their upper edges. For this purpose, a hooked finger, as 51, (Figs. 1, 5, and 7) or 52 (Fig. 8) is employed. These hooked fingers extend over the top of the radiator and they each have an enlarged 100 head 53 which is slidingly engaged with a chambered base block 54 mounted on the wall plate 10 or bearing plate 43. In the form of construction illustrated in Fig. 5, the base blocks 54 at the two sides of the 105 bearing plate 43 are united therewith by a common bolt 55.

Usually the top guide finger, as 51, will be adjustably held in position. As most clearly shown in Fig. 7, this is accomplished 110 by an adjusting screw 56 which extends vertically through the chamber of the corresponding base block 54 and has threaded engagement with the enlarged head 53 of the finger 51. Preferably the upper end 57 of 115 the adjusting screw 56 is both squared and slotted for operative engagement with either a wrench or a screw-driver (not shown). When a projecting window ledge 58 (Fig. 8) or the like would prevent access 120 to the adjusting screws 56, this screw may be omitted, in which case the enlarged head 53 of the corresponding finger 52 slides freely within the chamber of the base block 54. To guard against any possibility of 125 accidental disengagement of the finger 52 from the radiator, as 59, the finger 52 is made of such length as to normally overhang the upper edge of the radiator for a substantial distance.

I claim as my invention:

1. In a support for wall radiators comprising a plurality of parallel sections arranged in a common plane but at different levels, the combination with an upright bearing plate, of a saddle block projecting laterally from the bearing plate adjacent its lower end for supporting engagement with the underside of one radiator section, a bracket projecting laterally from the bearing plate intermediate its ends, means carried by the bracket constructed for guiding engagement with the upper edge of the last mentioned radiator section comprising a downwardly extending arm having a forked extremity, and means carried by the bracket for supporting engagement with the lower edge of the next higher radiator section and a hooked member carried by the bearing plate adjacent its upper end and engageable with the upper edge of the highest radiator section.
2. In a radiator support, in combination,

an upright bearing plate, a plurality of sets of base blocks secured to the bearing plate 25 at different levels, the base blocks of each set being upon opposite sides of the bearing plate, a vertically adjustable clamping bolt mounted in each base block and projecting outwardly therefrom, means carried 30 by each of the two lowermost clamping bolts forming a seat for the lower edge of a radiator section, means carried by each of the two next higher clamping bolts constructed for guiding engagement with the 35 upper edge of the corresponding one of the first mentioned radiator sections and for supporting engagement with the lower edge of another radiator section, and means attached to the bearing plate above the level 40 of the last mentioned clamping bolts and projecting outwardly therefrom in opposite directions for guiding engagement with the upper edges of the last mentioned radiator sections.

AUGUST KEHM.
